RACK FOR SEWING ACCESSORIES OR THE LIKE

James F. Leiring, Mira Loma, Calif.
(6205 Camino Maestro, Anaheim, Calif. 92307)

Filed Jan. 27, 1975, Ser. No. 544,868

Term of patent 14 years

Int. Cl. D6—04

U.S. Cl. D6—114

FIG. 2.

FIG. 3.

FIG. 1.

FIG. 4.

FIG. 6.

FIG. 5.

FIG. 1 is a front elevational view of a rack for sewing accessories or the like showing my new design;

FIG. 2 is a top plan view thereof;

FIG. 3 is a side elevational view taken from the left of FIG. 2;

FIG. 4 is a side elevational view taken from the right of FIG. 2;

FIG. 5 is a rear elevational view thereof; and

FIG. 6 is an enlarged fragmentary sectional view taken on line 6—6 of FIG. 1.

I claim:

The ornamental design for a rack for sewing accessories or the like, substantially as shown and described.
